UNITED STATES PATENT OFFICE.

GEORGE EDGAR HAZARD AND HARRY F. BOE, OF ROCHESTER, NEW YORK.

WASHING MACHINE.

Application filed February 2, 1922. Serial No. 533,678.

This invention relates to washing-machines of the type in which dishes, or other articles, are washed by discharging liquid sprays or jets against them, within a casing in which 5 they are supported by suitable foraminous or basket-like means.

One object of the invention is to improve machines of the type in question, with respect to the form and arrangement of the 10 work-supporting means and the spray-devices, so as to secure the most efficient and complete action of the spray, consistently with simplicity and convenience in the parts in question. Another object of the invention 15 is to improve the means by which the washing-fluid is strained in the course of its circulatory movement in the machine; and a third object is to provide simple and effective means for venting the machine in such a manner as to permit the discharge of air and vapor while preventing the escape of washing-fluid.

To the foregoing ends the invention resides in the several novel features of construction hereinafter pointed out in connection 20 with the description of the preferred embodiment of the invention.

In the accompanying drawings Fig. 1 is a side-elevation, partly in section, of a dish-washing machine embodying the present invention. Fig. 2 is a schematic plan-view of the spray-pipes, with some of the pipes shown in section. Fig. 3 is a vertical sectional view of one of the spray-pipes; and Fig. 4 is a plan-view of the strainer.

The invention is illustrated as embodied in a dish-washing machine, provided with a sheet-metal casing 5, of generally cylindrical form, this casing being open at the top and being supported on legs 6. A cover 7 35 is removably applied to the top of the casing to close it when the machine is in use.

The machine washes the dishes by subjecting them to sprays of water, the water being continuously circulated in the machine. An 40 electric motor 8, mounted below the casing, furnishes the power for this purpose, and drives a centrifugal pump 9 of any ordinary or suitable form. The water is drawn from an outlet-opening in the bottom of the casing, 45 through a strainer by which all solid particles, likely to clog the pump or the spray-orifices, are retained. This strainer, and the passage leading to it, have a novel form 50 which constitutes a feature of the invention. 55 The strainer has the form of a downwardly

expanding foraminous conical member 11. The water enters the strainer through the passage formed by a downwardly tapering conical member 10 and emerges through the perforations in the strainer. The tapering 60 forms of these parts are such as to facilitate the motion of the water, while at the same time tending to prevent clogging of the strainer. The stream of water is concentrated and its speed increased by the member 10, 65 and the solid particles therein tend, owing to gravity and their momentum, to be projected downwardly through the strainer 11 to the open lower end thereof, so that they may be separated from the water without being 70 forced against and into the perforations in the strainer.

The spray-device is revoluble, and it comprises a hollow branched body 12 which is pivoted on a post 13 rising from the bottom 75 of the machine. The pump discharges into the body 12, and the water then passes into four hollow arms or pipes 14 radiating from the body. The pipes 14 extend outwardly 80 near the bottom of the casing, and are then curved upwardly close to the wall of the casing, and terminate in four separable portions 15, 16, 17 and 18 respectively, which are provided with spray-orifices 19 from which the water is discharged against the dishes. 85

The orifices 19 are so formed as to project horizontal fan-like jets of water, and means are provided for supporting dishes within the space around which the spray-pipes revolve, and thus within the paths of these jets. For 90 this purpose a lower basket-like member is formed of heavy wires, including upright wires 20 which are bent outwardly at their upper ends and fixed to a ring 21. This ring rests loosely on a ledge 22 formed in the wall 95 of the casing, and by means of handles 23 the lower support may be lifted as a whole from the casing or replaced therein, for convenience in handling the dishes. When the support is in place, however, an annular space 100 for the revolution of the spray-pipes is provided by the form of the members 20, while the support depends into the space between the spray-pipes in such a manner that dishes 105 therein may be subjected most effectively to the jets from the orifices 19.

In addition to the lower support just described, there is an upper basket-like support located entirely above the spray-pipes. This 110 upper support is also formed of wires, and

comprises a base-ring 25 which rests normally on the ring 21. The wires of the upper support are so formed that the bottom of the support comprises several oppositely inclined 5 portions of generally-conical form, as clearly shown in Fig. 1, the illustrated device comprising, at the periphery, a downwardly and inwardly inclined part 28, inside of which is a part 29 upwardly and inwardly inclined 10 at a steeper angle, while the middle part 30 is downwardly inclined at a slight angle to the center.

The form of the upper support, just described, is particularly adapted to present 15 small deep vessels, such as pitchers, cups and tumblers, to the action of jets discharged in upward directions from the spray-pipes. Two or more of the pipes are flattened at their upper ends, so as to produce lips 27 between which the water is discharged in fan-like jets through wide angles in vertical radial planes, as indicated by dot-and-dash lines radiating from the pipe 16 in Fig. 1. An article such as a tumbler may be placed 20 in the upper support in several different positions, in each of which the water will be so discharged into it as to reach the bottom of its inner surface directly. Thus, if placed on its side on the part 28, with its top resting 25 against the part 29, the vessel will be held at such an angle that water discharged in the direction of the line 32 will pass across the diameter of the casing and enter the mouth of the vessel. If the vessel be 30 placed with its mouth resting on the part 28 of the support, water discharged in the direction of the line 31 will enter its mouth. A vessel resting with its mouth on the part 30 will receive water in the direction of the line 40 33. The upper support is provided with handles 26 by which it may be removed and replaced.

When hot water is introduced into the casing, with the cover 7 closed, the air there- 45 in is expanded, and air and vapor tend to escape. To permit this to occur without the discharge of water, the cover is provided with vent-openings so arranged as to baffle water while permitting free passage of air. For this purpose a downwardly-convex 50 sheet-metal member 34 is secured to the downwardly-concave middle of the cover, and into the space so enclosed the air may enter through a perforation 35 in the part 34, 55 while the air may escape through openings 36 in the cover. Any drops of water carried by the air will be arrested in the enclosed space, and will drain back into the casing.

The general arrangement of the casing, 60 the strainer and the pump are similar to that disclosed in our pending application for Letters Patent of the United States, Serial No. 384,779 filed May 27, 1920. The strainer is enclosed in a housing 37, which it fits closely at its lower end, and the bottom of this

housing forms a settling-chamber 40 in which solid matter may collect. From the housing both the solid matter and the water may be drained, when necessary, through a pipe 41 controlled by a valve 42 of any ordinary or suitable form. The strainer and the member 10 are combined in one removable assembly to facilitate cleaning, the upper end of the part 10 being provided with a marginal flange 39 which rests loosely in a recess provided in the bottom of the casing. 70 75

It has been found that the rapid motion of the water into the outlet tends to cause a whirling action by which the volume of the stream is greatly diminished. To prevent this the part 10 is provided with a baffle-plate 38 extending across the passage and this plate also serves as a handle by which the strainer assembly may be conveniently removed. 80 85

It should be noted that the strainer, when in place, constitutes a discharge-passage through which the liquid contents of the machine may be drained after completion of the washing operation. When the liquid is so drained it tends to flush away from the surface of the strainer any solid matter which has been deposited thereon in the performance of its normal function. 90 95

The revolution of the spray-pipes may be caused in any convenient manner, but in the illustrated machine the reaction of the water is utilized for this purpose. Fig. 2 shows, diagrammatically the arrangement of the spray-pipes, and as shown therein the pipes 16 and 18 are arranged to project the water from the orifices 19 at opposite inclinations, so to produce reaction which causes revolution of the spray-device in the direction of the large arrow in Fig. 2. The orifices 19 in the pipe 15 are directed radially inward. The orifices 19 in the pipe 17 are directed at a slight angle in the direction of revolution, as this has been found to promote the thorough subjection of the dishes to sprays from all directions. 100 105 110

Since the upper surfaces of the dishes in the upper support are not subject to the direct action of any of the sprays or jets, provision is made for subjecting them to the action of water dripping or rebounding from the cover 7 of the machine. For this purpose the spray-pipe 15 is provided with a discharge-opening, at its upper end, shaped to discharge a fan-like jet of water close to and parallel with the wall of the casing. This jet passes through the upper work-support near its periphery, at a point where it is likely to be relatively unencumbered with dishes, and impinges on the lower surface of the cover 7. Owing to the conical form of the cover, the water is deflected somewhat inwardly and then rebounds or drips upon the upper surfaces of the articles on the upper support. 115 120 125 130

For the admission of water to the machine, the casing is provided with an inlet-nozzle 44, which may be connected with any suitable source of supply.

5 It has been found that in spray-pipes with jet-openings in both their sides and their ends, the water, owing to its momentum, tends to discharge to an undue extent through the end-openings in preference to the lateral 10 openings. We have found that this tendency may be counteracted by the use of suitably placed baffles in the spray-pipes, and Fig. 3 shows three such baffles, 45, as used in the 15 pipe 16. The baffles extend from the wall opposite the openings 19, partly across the bore of the pipe and in a slightly inclined position. The uppermost baffle, as shown, is so located as to modify the form of the fan-like jet issuing from the top opening in the 20 pipe. As shown also in Fig. 3, the vertical part of each spray-pipe may be made as a separate member, adjustably fixed in the upturned end of the horizontal lower part of the same pipe, which is made of larger diameter for this purpose.

25 The invention is not limited to the embodiment thereof hereinbefore described and illustrated in the accompanying drawings, but it may be embodied in various other forms 30 within the scope of the following claims:

The invention claimed is:

1. A washing-machine comprising: a casing open at the top; a revoluble spray-device 35 consisting of a body rotatably mounted at the bottom of the casing, and spray-pipes radiating from said body and extending first outwardly, near the bottom of the casing, and then upwardly near its walls, the spray-pipes being provided with inwardly-directed openings in their upright portions and with upwardly directed openings at their upper 40 ends; a lower basket-like work-support suspended from the casing above the upper ends of the spray-pipes but depending into the 45 space about which they revolve; and a second basket-like work-support removably supported above the lower work-support, in

position to receive the spray from the upper ends of the spray-pipes.

2. A washing-machine comprising: a casing; a spray-device revoluble in the lower part of the casing, close to the wall thereof, and having openings arranged to discharge spray horizontally inwardly and also in an inwardly and upwardly-inclined direction; 55 a lower basket-like work-support suspended from the casing above the spray-device but depending into the space about which said device revolves; and an upper basket-like work support mounted in the casing entirely 60 above the spray-device and having a portion of its bottom formed as two concentric annular oppositely inclined surfaces to support hollow articles in positions suitable for receiving the upwardly-inclined spray. 65

3. A washing-machine comprising: a casing; a spray-device revoluble in the lower part of the casing and close to the wall thereof; and work-supporting means for supporting articles both above the spray-device and 70 within the space about which said device revolves; the spray-device comprising an upwardly-projecting tube provided with a contracted open upper end, horizontally-directed openings in its inner side, and inclined baffles extending partly across its bore from the side opposite the horizontally-directed 75 openings.

4. A washing-machine comprising: a casing open at the top; a cover for the top of the 80 casing; a spray-device revoluble in the lower part of the casing and close to the wall thereof; and work-supporting means for supporting articles in the upper part of the casing and in the space about which the spray-device 85 revolves; the spray-device being adapted to discharge spray inwardly, for direct action against said articles, and also to discharge spray upwardly to impinge against said cover at its periphery and be deflected thence to 90 the upper surfaces of said articles.
